COMBINED LOCK AND SWITCH

Boris Golokow and Samuel G. Chirlin, Buffalo,
N. Y., assignors of one-third to J. W. Lansing,
Buffalo, N. Y.

Application April 8, 1933, Serial No. 665,174

6 Claims. (Cl. 200—42)

This invention relates to improvements in locks for use in connection with burglar alarm circuits and more particularly the invention is concerned with a combined lock and switch, the 5 switch being associated with the lock in such a manner that an alarm is sounded if an unauthorized attempt is made to operate the lock either by picking or by a key other than the proper key.

10 One object of the invention is to provide a construction of the kind generally described in which the switch is incorporated in a lock of standard design.

A still further object is to provide a construction in which the circuit closing element of the switch is associated with the lock in such a manner that as it is moved to close an alarm circuit it assumes a position which will prevent 15 operation of the lock.

20 A still further object is to provide a construction which will enable the use of a key of standard design.

A still further object is to provide a lock having a switch associated therewith in such a manner that the alarm circuit is not closed 25 when the proper key is employed.

The invention is illustrated in the accompanying drawing, in which:

Figure 1 is a sectional view of a lock in which features of the invention are incorporated, the circuit for the alarm being shown diagrammatically.

Figure 2 is an enlarged fragmentary section taken along line 2—2 of Figure 1.

30 Figure 3 is a view similar to Figure 1 showing a modified form of circuit closing element, the said element being illustrated in the circuit closing position to which it is moved upon the insertion of an improper key in the lock.

Figure 4 is an enlarged perspective view of the 35 circuit closing element shown in Figures 1 and 2.

Figure 5 is a view similar to Figure 2 of another embodiment of the invention.

Figure 6 is an enlarged fragmentary section 40 taken along line 6—6 of Figure 3.

The alarm is illustrated, by way of example, in connection with a lock of the so-called Yale type. The lock, therefore, includes a barrel-like body 1 which is suitably secured in a door, the latter being sufficiently indicated at 8. The body 1 is formed with a flange 9 which fits 45 against the outer face of the door and with a longitudinal cylindrical chamber 10. A key holder 11 is rotatably mounted in the chamber 10, the said holder carrying a suitable cam or lever

12 which is adapted to operate the door bolt when the proper key is inserted in the lock and turned. The body 1 and key holder 11 are each formed with a series of bores 13 and 14 respectively, the bores of one series registering with 5 those of the companion series when the key holder is in the position in which the proper key may be inserted. Tumblers 15 and 16 are arranged in the bores 13 and 14 respectively. The tumblers 16 project into the key passageway and, 10 under the influence of springs 17 which are arranged behind the tumblers 15, assume a position in which the key holder 11, and hence the door bolt, is held against movement. Upon insertion of the proper key, which is indicated at 15 18 (Figure 1), the adjacent ends of the companion pairs of the tumblers are aligned with respect to the zone of division between the body 1 and the key holder 11 as is conventional in a lock of this type, whereby to permit turning of 20 the key holder to operate the door bolt.

In accordance with the invention means is provided whereby upon the insertion in the lock of a picking instrument or any key other than the proper key an alarm or warning signal is given. To this end the key holder 11 is formed with a recess 19, the latter being in alignment with the series of bores 14 in which the tumblers 16 are located. An element 20 is slidably mounted in the recess 19. Normally the element is retracted and lies wholly within the 25 said recess, whereby to permit turning of the key holder in the conventional manner when the proper key is inserted. When in this position the inner end of the element extends into the 30 key passageway. The key 18 (Figure 1) which is employed in connection with the lock is preferably of a standard design except that it is cut away at its forward end as at 18a so that the 35 said end will pass beneath the end of the element, when the key is inserted, without moving the element. In the embodiment shown in Figures 1 and 2 the element 20 is held in its retracted position by springs 23, the said springs being located in recesses 24 which are formed in the key holder 11 at opposite sides of the element. The springs 23 engage the projections 40 25 which are formed or provided upon the element 20 and resiliently hold the element in its retracted position.

The element 20 is adapted when engaged either by a picking instrument or a key other than the proper key, although the latter may be of a standard design with reference to the 45 particular type of lock, to be moved axially out 50 55

of the recess 19 against the action of the springs 23. This movement of the element 20 is availed of to close an alarm circuit. To this end the body 7 is provided with a recess 26 which, when 5 the key holder 11 is adjusted to permit operation of the tumblers, is aligned with the recess 19 in which the element 20 is located. Hence, as 10 the element 20 is moved axially out of the recess 19 the head 20a thereof enters the recess 26. A conductor 27 is arranged axially of the recess 26, the said conductor terminating in a contact 28 and being insulated from the body 7 by an insulating sleeve 27a. The latter is adapted to 15 support the contact 28 at a short distance from the entrance to the recess 26, whereby as the head 20a of the element enters the recess it engages the contact 28.

The conductor 27 is connected by a wire 29 to one side of a coil 31 of the electric magnet, the 20 other side of the coil being connected by a wire 32 to one side of a battery 33. The other side of the battery is grounded by a wire 34 to the body 7. An alarm or other suitable signalling device 35 is connected by a wire 36 to the wire 25 34 and by a wire 37 to a terminal 38. The said terminal is connected by a wire 39 to the stem 40 of a bridge-piece 41. The latter is located in spaced relation with respect to the poles of a permanent magnet 42 of the horseshoe type, the 30 spacing between the poles of the permanent magnet and the bridge-piece being such that the magnet of itself is not capable of pulling the bridge-piece against the said poles. A bar 43 which is arranged in the coil 31 is located in close 35 proximity to the bridge-piece whereby upon energization of the coil the bar is magnetized and the bridge-piece is pulled upwardly against the poles of the permanent magnet, the latter being capable of holding the bridge-piece 40 when it is moved to this position. The permanent magnet 42 is connected by a wire 44 to the wire 32. Hence, upon movement of the bridge-piece against the poles of the permanent magnet the bridge-piece is electrically connected to 45 the wire 32.

From the foregoing it will be apparent that when the element 20 is moved against the contact 28 a circuit is completed through the coil 31, the said circuit including conductor 27a, 50 wire 29 to one side of the coil, wire 32 which is connected to the opposite side of the coil to battery and battery to ground. Upon energization of the coil 31 the bridge-piece 41 is pulled against the poles of the permanent magnet 42 and a circuit is established through the alarm 55 35, the said circuit including one side of the battery 33, wire 32, wire 44, bridge-piece 41, stem 40 thereof, wire 39, terminal 38, wire 37 to one side of the alarm 35 and wire 36 from the other 60 side of the alarm to the other side of the battery. It will be apparent, therefore, that when the bridge-piece 41 is moved against the poles of the permanent magnet 42 it will be held in this position even though the element 19 may be 65 moved to break the circuit through the coil 31. The circuit, therefore, which is established through the alarm 35 will be maintained until the bridge-piece 41 is moved out of contact with the poles of the permanent magnet 42. The 70 bridge-piece may be moved to break the circuit through the alarm by a control element 45, the said element being mounted upon a pin 46. The element is normally held at one end of the pin by a spring 47. At its upper and lower ends 75 the element is formed with oppositely extending

fingers 48 and 49. The former is adapted to be grasped to move the element downwardly against the action of the spring 47 while the latter extends into the path of a projection 50, which is formed on the stem 40 of the bridge-piece 41, whereby as the element 45 is moved downwardly the finger 49 engages the projection 50 to pull the bridge-piece away from the poles of the magnet 42. It is understood, of course, that the warning device 35, control element 45 and associated mechanisms may be located upon the back of the door with which the alarm is associated or at any convenient point within the house and that, if desired, the alarm may be incorporated in any conventional type of burglar alarm system.

In the embodiment shown in Figure 5 the circuit closing element 51 is of a cross-section similar to that of the tumblers. It is normally located wholly within a passage 52 which is 20 formed in the key holder and the lower end thereof terminates in the key passageway at such a point that when the proper key is inserted the forward end of the key passes beneath the element, without moving it, as described in connection with the embodiment shown in Figure 1. In this embodiment the use of the springs, such as the springs 23 (Figure 2), for holding the circuit closing element in its retracted position is dispensed with, the 30 said element normally assuming and maintaining, by gravity, its fully retracted position. Upon the insertion of an improper key (indicated at 18a) or in the event that an attempt is made to pick the lock it is moved axially to 35 close the circuit through the alarm device in the manner described. It will be apparent that in the two embodiments described the circuit closing element is normally located wholly within the key holder and that its position is not 40 disturbed when the proper key is inserted in the lock. The said element is only moved from its retracted position when a picking instrument or an improper key is inserted in the lock. In such a case as the element moves to 45 its circuit closing position it locks the key holder, and hence the bolt operating mechanism, against movement.

In the embodiment illustrated in Figures 3 and 6, the circuit closing means consists of co-operating elements 53 and 54 which are similar 50 to the tumblers 15 and 16. The said elements are located in recesses 53a and 54a which are formed in the body and key holder respectively of the lock. Normally the elements 54 55 are seated in the bottom of the recess 54a and the element 53 is located partially within the recess 53a and partially within the recess 54a as indicated in dotted lines in Figure 6. The elements, therefore, while in this position 60 prevent rotation of the key holder and hence operation of the lock. Upon the insertion of the proper key in the lock the elements are moved to the full-line position shown in Figure 6, that is to say to a position in which the elements are located wholly within their respective recesses. When so located the key holder may be turned to operate the lock. In the event that an improper key 55 (Figure 3) is inserted in the lock the element 54 enters 70 the recess 53a and causes the element 53 to engage the contact 28 thereby connecting the contact 28 to ground and completing the circuit which includes the alarm device 35. It will be apparent, therefore, that the circuit 75

closing elements are similar to and function in substantially the same manner as the pairs of tumblers 15 and 16. The elements 53 and 54 may, therefore, be utilized, in addition to their primary function, as one of the sets of the tumblers. Hence the lock and the key therefor may be of standard construction. A further advantage obtained is that in the event that an attempt is made to remove the entire lock from the door, the element 53 will move by gravity to close the alarm circuit as soon as the body of the lock is turned over.

From the foregoing it will be apparent that the circuit closing elements are so located that in the event that the proper key is inserted in the lock the latter is permitted to operate in the conventional manner. If, however, an unauthorized attempt is made to operate the lock an alarm is given and the circuit closing element in its movement to close the alarm circuit assumes such a position that the lock cannot be operated.

We claim as our invention:

1. A lock for controlling a burglar alarm circuit, said lock including a body to which one side of said circuit is adapted to be grounded, a key holder having a key passageway formed therein, said body and key holder being formed with cooperating recesses in which tumblers are arranged and which are aligned to permit a key to be inserted in said key passageway, a contact terminal which is adapted to be connected to the other side of said circuit and which is insulated from said body and an electrically conductive element which is grounded to said body and which extends into said passageway, said element being movable to engage said contact terminal and connect it to ground, thereby to close said alarm circuit, said element being normally spaced from said contact and being so formed that the proper key to said lock may be inserted in said passageway without moving it to such an extent as to engage said contact terminal, whereby to prevent closing said alarm circuit when the proper key is used.

2. A lock for controlling a burglar alarm circuit, said lock including a body to which one side of said circuit is adapted to be grounded, a key holder having a key passageway formed therein, said body and key holder being formed with cooperating recesses in which tumblers are arranged and which are aligned to permit a key to be inserted in said key passageway, a contact terminal which is adapted to be connected to the other side of said circuit and which is insulated from said body and an electrically conductive element which is grounded to said body and which extends into said passageway, said element being movable to engage said contact terminal to connect it to ground and thereby to close said alarm circuit and being operative when so moved to lock said body and key holder against relative movement, said element being normally spaced from said contact and being so formed that the proper key to said lock may be inserted in said passageway without moving it to such an extent as to engage said contact terminal or to lock said body and key holder against relative movement.

3. A lock for controlling a burglar alarm circuit, said lock including a body to which one side of said circuit is adapted to be grounded, a key holder having a key passageway formed therein, said body and key holder being formed

with cooperating recesses in which tumblers are arranged and which are aligned to permit a key to be inserted in said passageway, a contact terminal which is adapted to be connected to the other side of said circuit and which is insulated from said body and an electrically conductive element which is grounded to said body and which is located wholly in one of said recesses, said element being normally spaced from said contact terminal and being movable to engage it and connect it to ground thereby to close said circuit, said element being so formed that the proper key may be inserted in said passageway without moving it to such an extent as to engage said contact terminal, whereby to prevent closing of said alarm circuit when the proper key is used.

4. A lock for controlling a burglar alarm circuit, said lock including a body to which one side of said circuit is adapted to be grounded, a rotatable key holder having a key passageway formed therein, said body and key holder being formed with companion series of recesses which are aligned to permit insertion of a key, tumblers in said recesses and a contact terminal which is carried by, but insulated from, said body and to which the other side of said circuit is adapted to be connected, one of said tumblers being normally spaced from said contact terminal and extending into said passageway, said tumbler occupying such position when the proper key is inserted in the lock, whereby to keep said circuit open and being movable, as upon the insertion of an improper key, to connect said contact terminal to ground and thereby close said alarm circuit.

5. A lock for controlling a burglar alarm circuit, said lock including a body to which one side of said circuit is adapted to be grounded, a rotatable key holder, said body and key holder being formed with companion series of recesses which are aligned to permit insertion of a key, pairs of tumblers in said recesses and a contact terminal which is carried by, but insulated from, said body and to which the other side of said circuit is adapted to be connected, one of said pairs of tumblers having electrical contact with said body, said tumblers being normally spaced from said contact terminal to lock said body and key holder against relative movement and being so formed that upon insertion of the proper key they are moved, without engaging said contact terminal, to a position in which they enable relative movement between said body and said key holder to permit operation of said lock without closing said circuit, said tumblers being adapted upon movement beyond said position, as upon the insertion of an improper key, to engage said contact terminal and connect it to ground and thereby to close said alarm circuit.

6. A lock for controlling a burglar alarm circuit, said lock including a body to which one side of said circuit is adapted to be grounded, a rotatable key holder, said body and key holder being formed with companion series of recesses which are aligned to permit insertion of a key, pairs of tumblers in said recesses and a contact terminal which is carried by, but insulated from, said body and to which the other side of said circuit is adapted to be connected, one of said pairs of tumblers having electrical contact with said body, said tumblers being normally spaced from said contact terminal to lock said body and key holder against relative movement and

being so formed that upon insertion of the proper key they are moved, without engaging said contact terminal, to a position in which they enable relative movement between said body and said key holder to permit operation of said lock without closing said circuit, said tumblers being adapted upon movement beyond said

position, as upon the insertion of an improper key, to engage said contact terminal to close said circuit and at the same time lock said body and key holder against relative movement.

BORIS GOLOKOW.
